ELMER E. VINSON, OF SAN FRANCISCO, CALIFORNIA

PUMPING SYSTEM

Application filed December 5, 1928. Serial No. 323,820.

This invention relates to certain improvements in apparatus for raising quantities of water to suitable elevations where the same may be available for the operation of devices used in the generation of electrical power.

My improved apparatus comprises, in brief, one or more pumping units having means embodied therein for elevating by gravity, suitable quantities of water to be used in producing electrical energy. The unit is provided with a float having a plunger secured thereto in such a manner that it fits into a compression chamber adapted to receive quantities of water. The float is movably located in a tank, and through suitable conduits sufficient water is admitted to the tank from the sea or other suitable source to elevate the float, whereby upon its being again lowered by the lowering of the water level in the tank, the plunger is permitted to operate in the compression chamber to force the water therein to a suitable receptacle such as an elevated storage reservoir, where it is available for any desired purpose.

An object of my invention is to provide apparatus for elevating quantities of water to desired elevations by the power of gravity, whereby it may be available for use in producing electrical energy.

Another object of my invention is to provide an improved hydro-electric power system comprising one or more pumping units which is actuated by the rise and fall of water therein to elevate quantities of water to desired elevations.

Other objects more or less apparent will present themselves or will be specifically pointed out in the description to follow.

In the accompanying drawings which show the preferred embodiment of my invention,

The figure is a vertical sectional view of my improved pumping apparatus.

My improved pumping apparatus consists of a tank 1, positioned preferably beneath the level of the sea and connected to the latter by one or more pipes 2, through which suitable quantities of water may proceed to and from the tank, dependent upon the rise and fall of the tide. Movably located in the tank 1 is a float 3 carrying a side 4 which

is secured thereto, and also a telescoping extension side 5 which fits tightly against the side 4 but still is adapted to move up and down therein. The top of the side 5 is enclosed by a movable cover 6 having a plunger 7 secured to its underneath surface. The plunger 7 slidably fits inside a cylinder 8 which is secured to the float 3 at points around a central cut out portion in the latter. Extending through the float 3 with their ends revolvably attached to the top and bottom of the tank 1 are a number of standards 9 which are provided with threads thereon with screwably operate in threaded lugs 10, secured to the extension side 5. Partly imbedded within float 3 and extending vertically above the top of the tank are a plurality of stand pipes 11 which communicate with openings 12 located in the bottom of the float, the said openings 12 in turn communicating with the inside of the cylinder 8 through the large central cut out portion in the float 3. The pipes 11 being connected to the inside of the cylinder 8 are adapted to receive quantities of water ejected from the said cylinder by the plunger 7 moving downwardly. A valve 13 located in the bottom of the plunger 7 may be opened and closed by a rod 14 which extends upwardly through an opening through the plunger, the said rod being rotated through connecting gears 15 and 16 by a motor 17. The motor 17 is adapted to operate in a direction to open the valve 13 by the meeting of contact plates 18 and 19, the latter plate being connected to a source of electricity and mounted on the side 5, and the former plate being mounted on the cover of the side 5. The motor 17 is adapted to operate in a reverse direction to close the valve 13 by the meeting of contact plates 20 and 21, the former contact plate 20 being supported by the cover 6, and the latter contact plate 21 being mounted on the side 5 and connected to the source of electricity. A second motor 22 is connected by a shaft 23 through gears 24 and 25 with standards 9, thereby affording means for raising and lowering the telescopic side 5 inside side 4. The said motor is actuated in a direction to turn the shaft 23 in a direction adapted

to lower side 5, by the meeting of contact plates 20 and 21 which are suitably connected to the said motor. The motor 22 is operated to turn the shaft 23 in a reverse direction so as to raise side 5 by the meeting of two other contact plates 35 and 36 which are also connected to the said motor. A contact plate 39 is mounted on the side 5 while another contact plate 38 is attached to a small float 37 which is moved upward and downward by the rising and falling of the water in the tank 1, due to the rise and fall of the tide of the sea. These contact plates 38 and 39 upon meeting cause the motor to turn the shaft 23 so as to lower the side 5.

Attached to the underneath surface of the bottom of the float 3 is a plunger 26 which movably fits inside a cylinder 27 secured to the bottom of the tank 1. The cylinder 27 is provided in its side with a one way inlet valve 28 and its inside is connected through outlet 29 with pipe 30 which is provided with a check valve 31, the said check valve functioning to prevent water from flowing back into the cylinder 27 through the said pipe 30. An opening 33 in the side of the float 3 connects with an air vent 34, thereby providing means for the passage of air to and from the inside of the float. A contact plate 40 mounted on the cover 6 and connected with the source of electrical energy is adapted to contact with another contact plate 41 secured to one of the pipes 11, thereby causing a motor 42, to which the contact plates are connected, to operate to open a valve 43 which is connected to the operating shaft of the motor by suitable gears 43^a, 43^b and an upright rod 43^c, thus allowing water to enter the stand pipes 11 from the tank 1 and pass into the cylinder 8. Suitable guides 44 located between the cover 6 and the bottom of the float 3 serve to insure the smooth upward and downward movement of the cover 6 within the side 5. Similar guides 45 are provided between the bottom of tank 1 and the bottom of float 3 to insure the smooth vertical movement of the float 3 in an upward and downward direction. A switch 46 connected to the wires leading to motors 17, 22 and 42 from the source of electrical energy, serves to turn on or shut off the flow of electricity coming to the apparatus.

Assume that the water in the tank has reached the high tide mark and that the float 3 has been raised with the top edge of the extension side 5 located a few inches above the water level in the tank and the cover 6 is located approximately flush with the top edge of said side 5. At this time the switch 46 is closed, thereby allowing the current to flow to the motor 17 through the contacting of the contact plates 18 and 19. The said motor is thereby actuated in such a direction that the valve 13 is opened to allow the water in cylinder 8 to pass upwardly through the

central opening in the plunger 7 and onto the top of cover 6. The weight of the plunger 7 and the cover 6 causes the plunger 7 to sink downward into the cylinder 8. The area of the plunger 7 being much less than the area of cover 6, the depth of the water thus transferred to the top of the latter is much less than the depth of the water removed from the cylinder 8 to the top of cover 6 by this action, leaving the cover 6 and the water thereon considerably below the top edge of the extension side 5 and also below the water level in tank 1. The movement of the cover 6 in a downward direction carries the contact plate 20 into engagement with contact plate 21, thereby closing another circuit to the motor 17 which rotates in a reverse direction to close the valve 13. The engagement of these same contact plates 20 and 21 causes motor 22 to operate in a direction to turn the vertical standards 9 in the lugs 10 so the extension side 5 is lowered to a desired position below the level of the water in tank 1, thereby causing the water in the tank to flow over the upper edge of the side 5 and upon the cover 6. The weight of the water on the cover 6 forces the cover and plunger 7 down still farther into the cylinder 8. The downward movement of the plunger 7 in the cylinder 8 forces the water in the said cylinder through the openings 12 into the stand pipes 11 where it at all times maintains an exact equilibrium with the pressure of the water supported by the cover 6.

When the cover 6 reaches a certain point in its descent, the weight of the water in the movable extension side 5 and above the cover 6 is such that it forces the float 3 and the plunger 26 downward with sufficient pressure that the water in the cylinder 27 is forced through the pipe 30 into reservoir 32. As the float 3 descends the water in the tank continues flowing over the top edge of the extension side 5 and upon the cover 6, thereby causing the plunger 7 to descend still farther so as to force the water in the cylinder 8 out into the stand pipes 11, where it rises to a still higher elevation.

When the bottom of the float 3 reaches the top edge of the cylinder 27, the water in the latter has been emptied, and the contact plates 35 and 36 have been brought into contact with each other. The engagement of the contact plates 35 and 36 closes another circuit to the motor 22, thereby causing the said motor to operate in a direction to turn the standards 9 in a reverse direction and elevate the extension side 5.

When the tide has fallen so the level of the water in the tank is at the desired level below the water in the extension side 5, the small float 37 has descended so as to cause the meeting of contact plates 38 and 39. The meeting of the contacts 38 and 39 closes another circuit to the motor 22, thereby causing

the motor to turn in a direction reverse to its last mentioned operation. The standards 9 are again actuated to lower the extension side 5 so that the latter's upper edge is even with or below the water level in the tank; thereby permitting water from inside the extension side 5 to flow by gravity back into the tank. At the same time that the pressure of the water on the cover 6 is removed, the water in stand pipes 11 flows back into the cylinder 8, thereby raising plunger 7 to the point it was when valve 13 was closed. When the cover 6 moves upward contact plate 40 is carried with it, thereby causing a contact to be made between contact plates 40 and 41, which closes the circuit to motor 42. The motor 42 is thereby made to operate to open valve 43, thus permitting the gradual flow of water into the cylinder 8 through 11 and 12. The water again entering the cylinder 8 moves the piston 7 and the cover 6 to their former positions, thus restoring the air space between the float 3 and the cover 6. The restoring of the air space as described causes the float 3 with its side 4 to rise, the cover 6 in the meantime having been forced upwardly until the said cover again becomes flush with the top edge of the extension side 5. This movement of the cover 6 to its former position causes the contact plate 18 to come into engagement with the contact plate 19, thus commencing another operation of the apparatus as described. As the plunger 26 is lifted upward in cylinder 27, the check valve 31 closes and holds the water in a suspended state in the pipe 30. The valve 28 in the cylinder 27 has opened during the upward movement of the plunger 26, thereby allowing sufficient quantities of water to enter and fill the said cylinder 27, preparatory to the next pumping movement of the float and its appurtenances.

The various contact plates, circuits and connections shown on the drawings are subject to various changes in both construction and position, it being understood that the forms shown are intended primarily for illustration purposes.

By constructing my improved pumping apparatus in other forms than the one shown, but by still utilizing the principles described, quantities of water from fresh water streams may be raised to desired elevations. It is apparent to those skilled in the art that my invention may be constructed in other forms than the one shown and described, so for this and other apparent reasons I desire my invention included broadly within the spirit of the appended claims.

Having described my invention, what I claim is:

1. Apparatus of the class described comprising a tank, having an inlet, a float movably located in the tank, carrying a plurality of telescopic sides, a cylinder carried by the

float, a cover movably fitting inside the sides, carrying a plunger movably fitting inside the cylinder, means for allowing water to pass upward through the plunger, a cylinder attached to the tank, a plunger carried by the float and adapted to fit inside the cylinder attached to the tank, means associated with each cylinder for allowing water to pass to and from the cylinders, and means for elevating and lowering one of the sides. 70

2. Apparatus of the class described comprising a tank having a water inlet therein, a float movably located in the tank, a plurality of telescoping sides carried by the float, the uppermost of the sides having a cover movably located therein, means for raising and lowering the upper side, a cylinder attached to the float having water carrying pipes connected thereto, a plunger attached to the cover and operating in the cylinder, a cylinder attached to the tank having an inlet and an outlet, a piston attached to the float and operating in the cylinder attached to the tank, and means for allowing water to pass from the cylinder attached to the float to the top surface of the cover. 75

3. In apparatus of the class described, a tank having a water inlet and outlet, a float located in the tank and adapted to rise and fall with the water in the tank, means mounted on the float for increasing and decreasing the weight of the float, whereby the float may be raised and lowered, a cylinder having a water inlet and a water outlet, and a piston carried by the float and operating in the cylinder chamber to draw water into the cylinder and to expel it therefrom. 90

4. In apparatus of the class described, a tank having a water inlet, a float movably located in the tank, means mounted on the float for increasing and decreasing the buoyancy of the float, whereby the float may be raised and lowered and means actuated by the rise and fall of the float for pumping water from the tank to an elevated reservoir. 105

5. In apparatus of the class described, a tank having a water inlet, a float movably located in the tank, a cylinder mounted on the float, having a movable cover thereon, means associated with the cylinder for allowing water to flow onto cover, whereby the float may be lowered, means for removing the water from the top of the cylinder whereby the float may be raised, a second cylinder located inside the tank having an inlet and an outlet, and a piston carried by the float and operating inside the second mentioned cylinder. 110

6. In apparatus of the class described comprising a tank having a pumping mechanism therein, the said pumping mechanism including a float, means for increasing and decreasing the buoyancy of the float whereby the float may be raised and lowered, a cylinder mounted in the tank, and a piston carried by 120

the float and movably located inside the cylinder.

7. In apparatus of the class described comprising a tank having a water inlet and outlet, a float movably located in the tank, water supporting means movably mounted on the float, means for delivering water to and from the water supporting means, whereby the float may be raised and lowered, a cylinder mounted in the tank having an inlet and an outlet, and a plunger carried by float and located in the cylinder, the said plunger being adapted to move upwardly with the float to draw water into the cylinder and to move downwardly with the float to expel water from the cylinder.

8. In apparatus of the class described comprising a water containing tank having an inlet and outlet, a float movably mounted in the tank, means for increasing and decreasing the buoyancy of the float, whereby the float may be raised and lowered, and a pumping mechanism operated by the raising and lowering of the float, which said mechanism includes a cylinder located in the tank having an inlet and outlet, and a plunger carried by the float and located in the cylinder.

In testimony whereof I affix my signature.
